CLAIM

The ornamental design for a storage case for gun powder and shot, as shown and described.

DESCRIPTION

FIG. 1 is a front, top and side perspective view of the storage case for gun powder and shot embodying the design of the present invention in open position;

FIG. 2 is a side elevational view thereof, in closed position the side opposite being a mirror image of the side shown in FIG. 2;

FIG. 3 is a rear elevational view thereof;

FIG. 4 is a top plan view thereof; and,

FIG. 5 is a bottom plan view thereof.
